THERMOMECHANICAL CONTROL SYSTEM

Hans Jakob Frey, Zollikon, Switzerland, assignor
to Edgar Gretener, Zurich, Switzerland

Application December 29, 1949, Serial No. 135,625

27 Claims. (Cl. 314—63)

1

The present invention relates to an improved thermo-mechanical control system of the kind which effects electrical or mechanical switching or coupling operations at a certain critical temperature or radiation value.

The invention is especially suitable in applications where the variations in the changes in temperature or radiation necessary to effect the control as well as the actual energy quantities available for control are, in themselves, relatively small. A particular application of the invention is in the control of the feed of the electrodes to an electric carbon arc lamp although it is to be understood that the invention is not limited to such specific use since it is equally applicable to control systems of a similar nature.

Various thermostatically operated systems were devised in arriving at the present invention for controlling the carbon feed to an arc lamp. These systems comprised, for example, a bimetallic strip which makes or breaks an electrical circuit feeding a motor driving the carbon feed mechanism in direct response to the carbon position, an image of the end of which is focused on the bimetal strip.

Where the actual contacts for operating the make-and-break circuit are disposed on the bimetallic strip or strips themselves, it was found that undesirable sparking occurs just as the circuit is being made or broken because there is an intermediate period of "semi-contact" which has the effect of producing an indeterminate control at the very time when a definite control action is needed.

One object of this invention is to provide a temperature or radiation sensitive control system which closes or opens contacts with positive snap action and is also simple and easy to manufacture.

A further object of the invention is to provide such a control system in which there is no mechanical load on the bimetallic strip or strips at the instant the contacts are operated.

It is an object of the invention to remove contact points from the bimetal strips.

The actual electrical contacts, or their mechanical equivalents, are therefore removed from the temperature sensitive bimetal strip or strips and incorporated in a subsidiary part of the control system operated by a control element having an active and an inactive position. The control element is actuated by the bimetal strip and returned by a separate mechanical source of energy.

In the thermo-mechanical control system ac-

2

cording to this invention the control element is tested periodically and, thereafter, depending upon the result, moved to the active or inactive position, as determined by the momentary influence of the radiation sensitive device at the testing time. This action initiates or suspends a controlling operation.

The active position may be such, for example, as to cause the control system to operate mechanism so as to feed the carbon electrodes to an arc lamp and the inactive position to suspend such feeding operation or vice versa.

Fig. 1 is a schematic elevation of one embodiment of the invention for controlling an electrical contact system.

Figs. 2 to 4 illustrate a further embodiment for controlling a mechanical spring clutch system, Figs. 3 and 4 being sections along lines A—A and B—B respectively of Fig. 2.

Figs. 5 and 6 are side elevation and plan views respectively of a modified form of bimetallic strip which may be employed in this invention.

Fig. 7 is a schematic plan view of one arrangement for the use of radiation selective means for increasing the contrast of a projected arc image when the system according to the invention is used for controlling the feed of the positive electrode to a carbon arc lamp, and

Fig. 8 is a graph illustrating the intensity of radiation from a high intensity arc lamp.

In the drawings like numerals refer to like parts throughout.

In Fig. 1 a bimetal strip 10 comprises the temperature sensitive element and is mounted at one end on frame 11 and provided with a projecting finger 12 at its free end.

The circuit to be controlled may include, for example, a small electric motor 13 and is completed through spring contacts 14 which are here incorporated as a part of the control system separate from the temperature sensitive bimetal strip 10. With this arrangement there is no mechanical load on the strip 10 when the contacts 14 are closed.

A kinematic control arrangement employing a tilting lever system 15 and 16 is used to operate the contacts 14. This tilting lever system is influenced on the one hand by the bimetal strip 10 and on the other hand by a separate source of energy such as a cam 17 provided, for example, with two rises 18 separated by relatively long dwells and driven at a substantially constant speed by a suitable source of energy such as a small synchronous motor the shaft of which is shown at 19.

The tilting lever system comprises a lever 15 pivoted at 20 and provided at each end, with head 21 and follower 22 mounted on opposite ends and sides thereof.

The arm 16 is mounted integrally and substantially at right angles with the lever 15 at the pivot 20. A tension spring 23 is connected between the end of the arm 16 and a part 26 of the frame 11 and exerts a torque on the lever system 15, 16. As shown in full lines in Fig. 1 this torque can be in a clockwise direction, whilst as shown in dotted lines it can be in an anti-clockwise direction depending upon the position of the lever. The arrangement is quite critical and yields snap action of lever 15 as the spring 23 passes over dead center at pivot 20.

The different directions of torque exerted by the spring 23 are due to the fact that the control lever system 15, 16 is in an approximately balanced condition mid-way between the two positions shown. The relatively light pressure exerted on lever 15 by the finger 12 of the strip 10 or the cam rises 18 is enough to cause it to move past center and tilt to the left or right, as the case may be. The tilting of lever 15 is biased by the action of the spring 23 in either an anti-clockwise or a clockwise direction.

The above control system operates in the following manner:

Relative cold will cause the strip 10 to tend to deflect upward in the direction shown by the arrow 24. In this position the head 12 of the strip 10 will limit the movement of the lever 15 to the position shown in full lines in Fig. 1 while the spring 23 will exert a clockwise torque on the end of the arm 16 which will tend to keep the lever 15 in the full line position shown, that is, out of contact with the make-and-break contacts 14. The two spring arms of the contact 14 completing the circuit through the feed motor 13 normally tend to bend apart and the circuit is closed only when the upper arm 14 is pressed down by the head 21 of the lever 15.

When the lever 15 is in the position shown in full lines the contact arm 14 is released and the circuit through the motor 13 is open.

An increase in radiation or temperature causes the strip 10 to deflect downward in the direction of the arrow 25 and to press finger 12 against the lever 15 until it snaps into the position shown in the dotted lines. Lever 15 forces head 21 against the contacts 14 which then close the circuit through the motor 13. In this latter position, as shown in dotted lines, the spring 23 exerts a counter-clockwise torque on the lever 15 as explained above after it passes beyond the dead center of pivot 20.

The position of the lever 15 shown in full lines can therefore be considered as an inactive one whilst that shown in dotted lines can be considered as an active one.

However, when the control lever 15 is in the second, or active, position it is subject to the action of the cam 17 with which the follower 22 comes into contact.

The cam 17 is rotated counterclockwise continuously by a separate source of power such as a motor geared to shaft 19 as shown by the arrow. As the twin cam rises 18 come into contact with the follower 22 the lever 15 is periodically subjected to a testing operation by being momentarily moved away from its active position by the action of the rises 18 on the follower 22. In the embodiment of the invention illustrated by Fig. 1 the testing action of the cam rises 18 is 75

to endeavour always to return the lever 15 from an active to an inactive position but the result of the test is dependent upon the momentary degree of deflection of the bimetal strip 10. That is to say, if the bimetal strip 10 moves the lever 15 down to the active position shown by the dotted lines and the radiation on or temperature of the strip 10 remains sufficiently high to keep the strip in such a critical deflected position the lever 15 will be returned to its active position after one of the rises 18 has depressed the follower 22 and lever 15 beyond dead center due to the anti-clockwise torque of the spring 23. The finger 12 of the strip 10 will have prevented the lever 15 from moving in a clockwise direction past the vertical axis, its critical balancing line about the pivot 20 which constitutes a fulcrum point for the levers 15 and 16.

On the other hand, if during the testing time 20 the radiation on or temperature of the bimetal strip 10 should fall sufficiently to allow this strip to resume its undeflected position the finger 12 will no longer be in contact with the lever 15 and will therefore not influence it as the cam rise 18 passes across the cam follower 22; in these circumstances the torque exerted by the spring 23 will be in a clockwise direction after the testing and the lever 15 will therefore return to the inactive position shown in full lines until it is again affected by the bimetal strip 10.

It will be appreciated that this thermo-mechanical system provides a very accurate and precise control and, at the same time, eliminates the necessity of having the electrical contacts 14 disposed on the bimetal strip 10. Furthermore, since in the critical testing position of the lever 15 the torque exerted by the tension spring 23 is virtually nil, and may in fact be adjusted to zero, the only load on the bimetal strip 10 is the negligible friction of the pivot 20. Because lever 15 experiences snap action the bimetal strip 10 operates in a practically unloaded condition, in the mechanical sense, at the instant contacts 14 are opened or closed. This is of vital importance to a very exact control where there is available only a relatively small amount and variation of temperature or radiation momentarily concentrated or focused on the bimetal strip 10. Tolerances are fairly close.

Fig. 2 illustrates a further embodiment of the invention in which the control lever 30, instead of opening and closing electrical contacts, operates an equivalent mechanical system consisting of a clutch which, for example, engages or disengages the carbon feed mechanism to an arc lamp according to the position of the lever 30.

In Fig. 2 an optical system 31 focuses an image 33 of an arc crater 32 at the end of the positive electrode in a carbon arc lamp on to the bimetallic strip 34.

In the embodiment illustrated, the bimetallic strip 34 constitutes part of a modified form of temperature sensitive element comprising two bimetallic strips 34 and 35 which are mounted on spring support 36 with spacing pieces 37 and connected together at their free ends by link 38. The arrangement is such that each strip 34 and 35 compensates that portion of the deflection of the other strip due to the ambient temperature. The two strips tend to deflect in response to temperature change and in opposite directions—either towards each other or away from each other. This action compensates or neutralizes the effect of changes of ambient temperature. A heat shield 40 is disposed between them in order to

prevent the radiation falling on one of them (e. g. the arc image focused on strip 4) from influencing the other.

This arrangement provides an exceedingly sensitive radiation responsive device with extremely accurate control as only tensile strain is exerted upon strips 34 and 35 by lever 30, whereby employment of very thin and consequently sensitive strips is made possible.

The two bimetallic strips 33 and 34 are mounted on a part 39 of the arc lamp frame 11 by means of a spring hinge support 38 which may consist of an extension of the shield 40, and a set screw 41 is provided for adjusting the position of the bimetallic strips 34, 35 relative to the lever 30 so that the operation of the control system can thereby be regulated.

The construction of the end 42 of the strip 35 is shown to better advantage by Fig. 3. This end 42 is made to co-act with one end of the control lever 30. The control lever 30 is pivoted at 43, as in Fig. 1, and loaded by the tension spring 44 connected between it and part 45 of the lamp frame 11 in such a way that a clockwise torque is exerted on the lever 30. The lower end of the lever 30 is formed as an angular projection 46 which co-acts with the cam 17. Cam 17 has two rises 18 which engage projection 46 and is continuously rotated in a clockwise direction by a suitable source of power such as a small motor on shaft 19.

The lever 30 constitutes a control element which is influenced by the temperature or radiation sensitive device consisting of the bimetallic strips 34, 35 and at the same time by the separate mechanical energy source driving cam 17.

The cam 17 forms part of a spring clutch device illustrated to better advantage by Fig. 4, which is a section on the line B-B of Fig. 2.

In Fig. 4 the cam 17 is mounted integrally with or keyed on a shaft 19 which is mounted in bearings 47 and continuously rotated at a virtually constant speed by a suitable motor. A toothed wheel 48 is mounted on the shaft 19 and adjacent to the cam 17. The wheel 48 is free to turn relative to shaft 19 when it is held stationary by the projection 46 of the lever 30.

A similar shaft 49 is mounted in bearings 50 co-axially with the shaft 19 and drives shaft 51 of Fig. 2 through suitable gearing such as a worm and gear. Shaft 51 drives shaft 52 through bevel gears 53, 54, and shaft 52, in turn, drives shaft 55 through bevel gearing 56, 57. Shaft 55 drives the mechanism 58 through bevel gearing 59, 60 and feeds the positive electrode 61 to the arc 62. Carbon feed mechanism 58 may comprise geared conical friction rollers as shown or other suitable mechanism.

The coupling between the driving shaft 19 and the driven shaft 49 is effected by means of a helical spring 63 which is coiled round and lightly grips the spaced apart ends of the two shafts 19 and 49. One end 64 of the spring 63 fits into and is held by a small hole in the toothed wheel 48.

The control system shown in Figs. 2 to 4 operates in the following manner:

The feeding mechanism 58 may be arranged to feed the positive electrode 61 at substantially its normal burning rate but, for practical reasons, a speed very slightly above this rate is preferred.

An image 33 of the arc 62, and preferably of the arc crater 32, is focused by lens 31 on the bimetallic strip 34. The amount of radiation thus concentrated on the strip causes it to de-

flect downwards toward the cam 17 of Fig. 2 as shown in dotted lines. The lower strip 35 is not affected by this radiation concentration because it is protected by the shield 40 and functions to correct the effect of changes in the ambient temperature.

As the strip 34 deflects downwards link 38 forces the end 42 of the strip 35 down as well. The end of the lever 30 resting against the end 42 is caused by the rises 18 of cam 17 to ride along the underside of this end piece 42 and enter the slot 65, Fig. 3, by which means the lever 30, and the follower 46 are held free from the wheel 48 as shown in dotted lines in Fig. 2.

This dotted position of the lever 30 constitutes the active position and the positive carbon is fed forward because the shaft 19 and cam 17 rotate continuously. Torque is transmitted to the shaft 49 through the spring 63 which in its unrestrained position grips the adjacent ends of the shafts 19 and 49 whereby motion is imparted through the shaft 51, gear train 53, 54 and shaft 52, etc., to the carbon feeding mechanism 58.

This condition holds good as long as an image 33 of the arc crater 32 is focused on the strip 34. However, should the end of the positive carbon 61 advance towards the negative carbon 66 an image 33 of the relatively colder end of the positive carbon 61 will be focused on the strip 34, instead of an image 33 of the intensely hot crater 32.

As a consequence, the cooler radiation concentrated on the strip 34 will cause it to bend upwards towards the carbons, as shown in full lines in Fig. 3, and free lever 30 from slot 65. The force exerted by the spring 44 will rotate the control lever 30 clockwise and bring the follower projection 46 into contact with the cam 17 and wheel 48 as shown in full lines. This position constitutes the inactive position for the control lever 30 with shaft 49 and mechanism 58 stationary.

In this inactive position the projection 46 will engage with the teeth of the toothed wheel 48 and hold it stationary. As the end 64 of the helical coupling spring 63 is held in a small hole in the wheel 48 this coupling spring 63 will also be held stationary and will, in practice, unwind slightly and cease to grip the end of the shaft 49. Consequently, the drive to the spindle 51 will discontinue and the carbon feeding mechanism 58 will become inactive and stop.

In this inactive condition, however, the control lever 30 will be periodically subjected to a testing operation by the rises 18 of the continuously rotating cam 17. The projection follower 46 will ride up the rises 18 and, depending upon the deflection of the bimetallic strips 34, 35 at that moment, the follower 46 and therefore the lever 30 will either be brought back to the inactive position by the tension of the spring 44 as shown in full lines, or will again be held in the slot 65 in the end 42 of the strip 35, that is, in the active position, as shown in dotted lines.

In the embodiment of the invention illustrated by Figs. 2 to 4 the purpose of the testing action of the cam rises 18 is to endeavor always to return the lever 30 from an inactive (or non-feeding) position to an active (or feeding) position but the result of the test is dependent upon the momentary degree of deflection of the bimetallic strips at the testing time. It will be appreciated, moreover, that movement of the bimetallic strips 34, 35 during the testing period takes place increment by increment without any load on them.

This is a most important practical advantage.

It will be seen that this arrangement provides an extremely fine and precise control to be effected on the carbon feed and makes it possible to hold the position of the arc within very close limits.

The invention is not restricted to the use of the precise arrangement of bimetallic elements shown in Figs. 1 and 2 as other suitable forms may be employed making use of the different co-efficients of expansion of at least two metals, such as a spiral or a helix.

Different methods of compensating for the effect of the ambient temperature may also be employed.

Figs. 5 and 6 illustrate one such modified arrangement employing a single bimetallic strip 70 which is particularly simple. Fig. 5 is a side view and Fig. 6 a plan view of the strip 10. The arrangement consists of a bimetallic strip which is compensated in itself to neutralise the effect of the surrounding temperature. This is done by twisting a strip 70 which is initially flat throughout its length. The strip 70 is twisted through 180° at the point 71 so that with an increase or decrease in the surrounding temperature the part 72 deflects in the opposite sense to the part 73 with the result that any such rise or fall in the temperature will not affect the working conditions of the bimetallic strip nor interfere with the effect of the radiation focused on the strip.

The best results are obtained if, with a given total length, the proportion of the twisted length 73 to the untwisted length 72 is 2.4:1. Only the part 72 is influenced by the concentrated radiation when such a construction is used.

To obtain a very sensitive and accurate control when employing the present invention to control the electrode feed to an arc lamp, it is desirable to have considerable contrast between the radiation at the edge of the positive electrode 61 and of the arc 62 or arc crater 32 imaged on the bimetallic strip.

Figs. 7 and 8 illustrate this to better advantage. In Fig. 7 the abscissa 89—80 represents the position relative to the arc and the ordinate 81—81 the relative intensity of the radiation from the arc 62. In Fig. 8 the abscissa 90—80 represents wave lengths from ultra-violet to infra-red in the direction shown by the arrow 91 and the ordinate 92—92 represents the relative intensity in the direction of the arrow 93.

The radiation 94 coming from the arc contains a great deal of ultra-violet rays whilst that from the shell of the end of the positive electrode 61 contains a great amount of infra-red rays as shown at 95. The contrast between the end of the electrode 61 and the arc crater 32 can be increased if the arc is concentrated into a substantially cylindrical form between the two electrodes by means of an air stream and the curve 82, Fig. 7 illustrates the relative intensity of such an arc.

This contrast can be enhanced still further and in practice almost doubled if colour selective means are employed to accentuate the differences in the radiation of the image focused on the bimetallic strip 10 or 34 by the lens system 31. These means can be very simple and can consist in colouring the surface of the bimetallic strip for example, with a red colour which will reflect the long wavelength radiation and absorb the short wavelength radiation or, alternatively or in addition, a colour selective filter 83 of the reflecting or absorption type may be inserted in

the image beam which filter will absorb or reflect the long wavelength radiation and allow the short wavelength radiation to pass through it obtaining a distribution of intensity as shown by curve 86. A masking diaphragm 34 having an opening 85 through which the arc image is projected may also be employed if desired.

Various details of the present invention possess considerable practical importance. The slight unwinding of spring 63 during the inactive stage causes it to retain its ability to grip the shaft 49 during the active stage. Otherwise increasing slippage and shortened control life would result.

Again the frequency of testing by cam rises 18 while not great frees the bimetallic strip and permits it to function without load. For accuracy of control and prompt response this construction yielding snap action both in Figs. 1 and 2 is of prime practical importance.

The foregoing disclosure is presented by way of example for illustrative purposes and is not to be taken as limiting. The following claims are intended to cover such other forms of the invention as may fairly and properly be regarded as falling within the spirit of the invention.

1. In a control system, a device to be controlled, circuit means for said device, a movable arm pivoted so as to assume an operative position in which it affects said circuit means to operate said device and to assume a second position in which said device does not operate, means to move said arm from one position to the other with snap action, bimetal means arranged to act upon said arm to cause it to assume said operative position and cyclic means arranged to repeatedly test the position of said arm, said cyclic means contacting said arm for test purposes, only when said arm is in said operative position whereby to move said arm to said second position abruptly when said bimetal means moves more than a predetermined distance from said arm.

2. The combination set forth in claim 1, said circuit means having contacts which are closed by said arm in its active position, said snap action means comprising a bias spring which moves quickly from one equilibrium position to another.

3. The combination set forth in claim 2 said cyclic means comprising a movable projection which repeatedly presses the side of said arm on the opposite side of the pivot from the point of action on said arm by said bimetal.

4. In an arc lamp control, a bimetal means, means to focus radiation from said arc upon said bimetal means thus causing deflection thereof, electrode moving means to adjust said arc, spring means, a lever pivotally mounted and being capable of assuming two different stable positions, said lever being mounted to actuate said electrode moving means when in one of said two positions, lever positioning means for periodically moving said lever means to a third transient position, a source of mechanical energy continuously driving said lever positioning means, said bimetal means being so mounted with respect to said lever to cause it to return under the influence of said spring means from said transient position to the one or the other of said two stable positions, if the deflection of said bimetal means is above or below a predetermined value, whereby said electrode moving means are actuated to adjust said arc only if said deflection is on one side of that predetermined value.

5. The combination set forth in claim 4, the

action of said lever on said electrode moving means being initiated only by said bimetal means which is unloaded when said lever moves to that position in which it affects said electrode moving means.

6. The combination set forth in claim 4, clutch means for driving said electrode moving means under control of said lever means.

7. In a thermo-mechanical control system, a control element movably mounted to take one of two positions, a temperature sensitive device acting upon said control element and selectively applying a first force thereto, means having a source of energy and which repetitively tests said control element by applying a second force thereto which acts intermittently only and is opposed to said first force, said control element including means responsive to said first and second forces and moving abruptly to one of said positions when the resultant of said first and second forces is at least a predetermined amount at the instant of test under the action of snap-action means whereby said control system is entirely operative or inoperative.

8. The combination set forth in claim 7, said test means comprising a cam which acts to move said control element from one of said positions.

9. The combination set forth in claim 8 said temperature sensitive device comprising a bimetal strip acting to hold said control element in one of said positions under selected temperature conditions.

10. The combination set forth in claim 8, said temperature sensitive device comprising a bimetal strip acting to move said control lever toward one of said positions and snap action means to complete said movement of said control lever.

11. The combination set forth in claim 1, means to compensate for the action of ambient temperature on said bimetal.

12. The combination set forth in claim 11, means consisting of a bimetallic strip with one end fixed, which is twisted through 180° and where the ratio of the length of the free twisted end to the length of the fixed untwisted end is 2.4:1.

13. The combination set forth in claim 4, means to compensate for the action of ambient temperature on said bimetal means.

14. The combination set forth in claim 4 means consisting of a bimetallic strip with one end fixed, which is twisted through 180° and where the ratio of the length of the free twisted end to the length of the fixed untwisted end is 2.4:1.

15. In a control system, a control device for initiating the action of said control system, comprising in combination, radiation sensitive means, actuating means, selectively coupled to said radiation sensitive means, control initiating means selectively coupled to said actuating means and initiating the action of said control system when affected by said actuating means, additional mechanical means selectively acting upon said actuating means, power means conveying a force to said actuating means to actuate said initiating means, a separate source of mechanical energy continually driving said additional mechanical means, said actuating means being so positionally arranged relative to said radiation sensitive means, initiating means, and additional mechanical means that it moves abruptly with snap action to either a first operative position in which it

affects the said initiating means, or to a second inoperative position in which said initiating means are not affected and where said additional mechanical means repeatedly restore said actuating means at regular intervals to an intermediate testing position from at least one of said first and second positions, so that said initiating means are affected when said radiation sensitive means is on one side of a certain critical value, and are not affected when it is on the other side of said critical value.

16. The combination set forth in claim 15, said radiation sensitive means comprising a bimetal device subjected to control radiation, said actuating means including means dependent upon the deflection of said bimetal device.

17. In a control system, a control device comprising in combination, a bimetal means, resilient means, a pivoted movable arm subject to the action of said resilient means, a cam means selectively acting upon said arm, a separate source of mechanical energy rotating said cam means at constant speed, and control initiating means for initiating the action of said control system when affected by said arm, said arm being biased by said resilient means to assume abruptly with snap action a first operative position in which it affects said initiating means or to assume a second inoperative position in which said initiating means are not operated, said cam means repeatedly restoring said arm to an intermediate testing position from at least one of said first and second positions, said arm being moved by said resilient means from said testing position to either of said two positions in response to a predetermined deflection of said bimetal means.

18. The combination set forth in claim 17, said resilient means being connected to said arm in such a way that said arm possesses an equilibrium position between said first and second positions so that said arm will move to said first or second position by snap action in dependence upon the deflection of said bimetal means which is unloaded by said arm when in said equilibrium position.

19. In an arc lamp control, a bimetal means, means to focus radiation from a carbon arc upon said bimetal means, electrode moving means to adjust said arc, lever means pivotally mounted, resilient means acting upon said lever means, cam means acting upon said lever means, a separate source of mechanical energy rotating said cam means at constant speed, control means to vary the action of said electrode, moving means influenced by said lever means, said resilient means acting upon said lever means and causing it to assume a first position to vary the action of said electrode moving means, said bimetal means when sufficiently deflected arresting the lever in a second position to permit unrestricted action of said electrode moving means, said cam means repeatedly moving said lever at regular intervals to a third testing position where the bimetal means may deflect under the effect of said radiation unloaded by said lever means and snap action means acting on said lever means to move it abruptly and completely from full operating position to inoperative position and vice versa.

20. The combination set forth in claim 19, where the electrode moving means are actuated by said source of energy through a clutch, said clutch being disengaged when said lever means assumes said first position and engaged when said lever means assumes said second position.

21. The combination set forth in claim 16, said bimetal means comprising two parallel bimetal strips mounted at one end and fixedly connected at the other end, tending to respond to variations of temperature by deflection in opposite directions, only one of said strips being subject to said radiation.

22. In a control system, a control device for initiating the action of said control system, comprising in combination, radiation sensitive means, actuating means selectively coupled to said radiation sensitive means, actuating means selectively coupled to said radiation sensitive means, control initiating means selectively coupled to said actuating means and initiating the action of said control system when affected by said actuating means, additional mechanical means selectively acting upon said actuating means, power means conveying a force to said actuating means to actuate said initiating means, a separate source of mechanical energy continually driving said additional mechanical means, said actuating means being so positionally arranged relative to said radiation sensitive means, initiating means, and additional mechanical means that it moves abruptly to either a first operative position in which it affects the said initiating means, or to a second inoperative position in which said initiating means are not affected and where said additional mechanical means repeatedly restore said actuating means at regular intervals to an intermediate testing position from at least one of said first and second positions, so that said initiating means are affected when said radiation sensitive means is on one side of a certain critical value, and are not affected when it is on the other side of said critical value said bimetal means comprising a bimetal strip fixed at one end which is twisted through 180° the ratio of the length of the free twisted portion and of the length of the fixed untwisted portion being 2.4:1, only one of said two portions being subject to said radiation.

23. The combination set forth in claim 16, the surface of said bimetal device subject to radiation being suitably colored so as to make it particularly sensitive to a desired part of the spectrum of radiation received.

24. The combination set forth in 19, the surface of said bimetal means subject to radiation being suitably colored so as to make said means particularly sensitive to a desired part of the spectrum of radiation received.

25. The combination set forth in claim 19 including selective filter means inserted between said carbon arc and said bimetal means, said filter means permitting radiation of a predetermined wavelength to pass, thereby making the device particularly sensitive to radiation emitted by the arc itself.

26. In an arc lamp control a bimetal means, means to focus radiation from said arc upon said bimetal means thus causing deflection thereof, said bimetal means being constructed to compensate for the action of ambient temperature, electrode moving means to adjust said arc, a lever pivotally mounted and arranged to control said electrode moving means, a spring, a constantly rotating cam wheel, said spring urging said lever against said cam wheel, said bimetal means being arranged to limit the movement of said lever when its deflection is on one side of a predetermined value, said cam wheel periodically bringing back said lever to a transient position thus permitting the bimetal means to deflect freely under the influence of said radiation, said lever being arranged to exert only tensile strain upon said bimetal means when held back thereby, whereby said electrode moving means are actuated by said lever only if the deflection of said bimetal means is on one side of said predetermined value.

27. The combination set forth in claim 4, means to compensate for the action of ambient temperature on said bimetal means, said bimetal means comprising two parallel bimetal strips mounted at one end and fixedly connected at the other end, tending to respond to variations of temperature by deflection in opposite directions, only one of said strips being subject to said radiation.

HANS JAKOB FREY.
